US0D1061876S

(12) **United States Design Patent** (10) **Patent No.:** **US D1,061,876 S**
(45) **Date of Patent:** **** Feb. 11, 2025**

(54) **FRAME FOR A MASK ASSEMBLY**

(71) Applicant: **Fisher & Paykel Healthcare Limited**,
Auckland (NZ)

(72) Inventors: **Roheet Patel**, Auckland (NZ); **Michael John Henri Cox**, Auckland (NZ); **Max Leon Betteridge**, Auckland (NZ); **Bruce Michael Walls**, Auckland (NZ); **Ronan Leahy**, Auckland (NZ); **Matthew James Pedersen**, Auckland (NZ); **Jae Yun Lim**, Auckland (NZ)

(73) Assignee: **Fisher & Paykel Healthcare Limited**,
Auckland (NZ)

(**) Term: **15 Years**

(21) Appl. No.: **29/902,512**

(22) Filed: **Sep. 13, 2023**

Related U.S. Application Data

(62) Division of application No. 29/730,639, filed on Apr. 7, 2020, now Pat. No. Des. 1,009,252, which is a division of application No. 29/643,155, filed on Apr. 4, 2018, now Pat. No. Des. 884,153.

(57) **CLAIM**

The ornamental design for a frame for a mask assembly, as shown and described.

DESCRIPTION

FIG. 1 is a front perspective view of a frame for a mask assembly.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines in the drawings illustrate portions of the frame for a mask assembly which form no part of the claimed design.

1 Claim, 7 Drawing Sheets
